(57) **CLAIM**

The ornamental design for a thermal chair cover, as shown and described.

DESCRIPTION

FIG. 1 is a perspective view of a thermal chair cover showing my new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof;

FIG. 7 is a bottom plan thereof; and,

FIG. 8 is a perspective view shown in its environment thereof.

In the drawings, the broken lines showing a chair in FIG. 8 form no part of the claimed design.
